UNITED STATES PATENT OFFICE

WALTER S. FINNELL, OF ELKHART, INDIANA

DESIGN FOR A FRAME FOR A MOPPING MACHINE

Application filed May 14, 1930. Serial No. 35,645. Term of patent 14 years.

To all whom it may concern:

Be it known that I, WALTER S. FINNELL, a citizen of the United States, residing at Elkhart, in the county of Elkhart, State of Indiana, have invented, a new, original, and ornamental Design for Frame for a Mopping Machine, of which the following is a specification, reference being had to the accompanying drawing, forming a part thereof.

In the drawing, Figure 1 is a perspective

view of a frame for a mopping machine showing my new design; and

Figs. 2 and 3 are, respectively, fragmentary showings of a side elevational view and a top plan view.

I claim:

The ornamental design for a frame for a mopping machine, as shown.

WALTER S. FINNELL.
